UNITED STATES PATENT OFFICE.

FRIEDRICH JOHANN DITRICH HÜLLINGHORST, OF LONDON, ENGLAND.

COOLER.

No. 872,427.

Specification of Letters Patent.

Patented Dec. 3, 1907.

Application filed March 13, 1907. Serial No. 363,221.

To all whom it may concern:

Be it known that I, FRIEDRICH JOHANN DITRICH HÜLLINGHORST, a subject of the Emperor of Germany, of 190 Blythe Road, 5 West Kensington Park, London, in the county of Middlesex, England, have invented a new and useful Improvement in Radiators or Coolers for Motor Road-Vehicles, of which the following is a specification.

10 This invention relates to improvements in radiators or coolers for use in reducing the temperature of the water that is circulated about the engine cylinders and other parts of motor road vehicles which become readily overheated.

15 The invention has more particular reference to that class of radiator or cooler in which an air propelling fan is combined with an annular chamber through which the heated water from the engines is caused to circulate and be cooled prior to its return thereto for further use.

20 The object of the present invention is to provide additional cooling spaces or passages surrounding the air-propelling fan in combination with means for conducting the current of air produced direct on to the motors or other parts to be cooled.

25 The invention consists essentially in providing radiators or coolers of the kind referred to with a secondary cooling chamber concentric with the annular chamber surrounding the air-propelling fan, supplemental cooling spaces disposed at the front and back of the radiator; intercommunicating pipes or connections between said annular chamber and the secondary and supplemental cooling spaces; and a series of short pipes or ducts, leading from the space between the 30 two annular chambers through one of the supplemental cooling spaces, by which the air is directed about the parts to be cooled.

35 In order that the invention may be more readily understood I will describe the same in reference to the accompanying drawings which are in illustration of my invention, Figure 1 being a front elevation of a radiator or cooler constructed in accordance with my improvements, the right hand half of the 40 figure being in section or broken away for the sake of clearness. Fig. 2 is a back exterior elevation of the same, and Fig. 3 is a transverse vertical section.

45 *a* is the outer annular chamber supported upon the base *b* and into which the heated water from the motor is forced through the

pipe *c* by the usual circulating pump not shown in the drawings.

d is the discharge pipe or outlet from radiator and from which the cooled water is 60 returned to the motor for fresh use constant circulation being thereby easily maintained.

In the present form of my invention I preferably make the outer annular chamber *a* of considerably smaller capacity than heretofore and internally and concentrically thereof I arrange a secondary cooling chamber *e* held in position in any convenient way. In the drawings the chamber *e* is shown as 65 nearly surrounding the air propelling fan *f* or somewhat in the form of a saddle connection between it and the outer chamber *a* being effected by means of short pipes *g*, *g*, *g'*, *g'*, the former *g*, *g*, being fitted at the upper side as inlet pipes from the chamber 70 *a* and the latter *g'*, *g'*, being disposed at the lower ends of the saddle and communicating with the base *b*.

75 It will be readily understood that the chamber *e* may be made completely annular and provided with apertures or openings therethrough for the passage of the air from the fan *f* instead of in the form shown.

80 *h* is the end plate for the front of the radiator which is made in the form of a hollow cover or supplemental chamber furnished with a central aperture *i* for the admission of cool air to the central part of the fan *f*.

85 *j*, *j'* are short pipes connecting the cover *h* with the annular chamber *a* and the base *b* respectively. In order that the proper connection and disconnection of the cover thereto may be easily effected I provide the pipes *j*, *j'* with flanges *k*', *k* arranged to be secured to the cover *h* by means of screws, 90 short cross over connections *l*, *l'* being provided for the passage of the water to and from both sides of said flanges as will be clearly understood on reference to Figs. 1 and 3 of the accompanying drawings.

95 *m* is the end plate or cover for the back of the radiator which is made in the form of a hollow supplemental chamber as described in reference to the front end cover *h*.

100 *n* is an annular chamber formed on or fixed to the back of the radiator and connecting with the chamber *a* through a passage *n'* (Figs. 1 and 3), with the base *b* by means of a passage *b'*, and with the end plate or cover *m* through passages *m'*, *m'*, *m*, *m'*, 110 (Figs. 2 and 3).

105 *o*, *o*, are short pipes or air ducts through

the annular chamber *n* communicating with the space between the chambers *a* and *e*. These air ducts I prefer to make somewhat conical or tapered as shown.

5 *p, p* are bearings fixed to the end plates *h* and *m* for the spindle *q* of the fan *f*.

10 *r* is an outlet connecting the lower part of the annular chamber *a* with the outer air for the purpose of allowing dirt or other material drawn into the radiator immediately to fall out again without any possibility of damaging the fan.

15 *s* is a cap provided with holes for the escape of any steam that should accumulate in the radiator and *t* is an overflow pipe.

20 In use, the fan *f* is set in revolution by means of a belt passing over the pulley *u* (Fig. 3) and heated water from the engine being forced into the radiator through the pipe *c* becomes thoroughly cooled during its circulation through the various chambers and passages before it reaches the return pipe *d* due to the absorption of the heat by the constant flow of cool air through the 25 device, and cool air being drawn in and driven round the space intervening between the annular chambers *a* and *e* and out through the short pipes or air-ducts *o, o*, on to the motor and other parts to be cooled thereby greatly assisting in keeping down 30 the temperature of the parts liable to overheating.

35 In practice I have found that by making the short pipes or air-ducts *o, o*, tapered or somewhat conical, as described, the objectionable noise consequent upon the air being forced therethrough is entirely obviated.

40 By my improvements the water is cooled in a thoroughly simple and effective manner, greater economy in space is insured, while the provision of a removable part to the radiator gives free access for purposes of lubrication and cleaning, better results are attainable than hitherto possible and the 45 entire apparatus is cheap to manufacture and not likely to get out of order.

50 The details of construction may be varied more or less to meet different conditions without departing from the nature of my invention.

What I claim as my invention, and desire to secure by Letters Patent, is:—

1. In radiators or coolers for motor road vehicles having an air-propelling fan disposed within an annular chamber, the combination of a secondary cooling chamber arranged concentric with the annular chamber surrounding said fan, supplemental cooling spaces provided at the front and back of the radiator, inter-communicating pipes or connections between said annular chamber and the secondary and supplemental cooling spaces; and a series of short

65 pipes or ducts leading from the space between the two annular chambers through one of the supplemental cooling spaces by which the air is directed about the parts to be cooled, substantially as described and shown.

2. In radiators or coolers for motor road vehicles of the kind hereinbefore referred to, the combination of an outer annular chamber, a secondary cooling chamber arranged within and concentric with the same, an air propelling fan surrounded by said annular chamber and provided with an opening or aperture for the air to be circulated between its exterior and the interior of said annular chamber, and inlet and discharge pipes for the circulation of water therethrough, substantially as described and shown.

3. In radiators or coolers for motor road vehicles of the kind hereinbefore referred to, and provided with a base, the combination of a hollow detachable end plate or cover for the front of the radiator provided with a central aperture for the admission of cool air, a fan to the central part of which said air is admitted, an annular chamber, and short pipes connecting said cover with the annular chamber and the base of the radiator for the circulation of water therethrough, substantially as described and shown.

4. In radiators or coolers for motor road vehicles of the kind specified and provided with a back and base, the combination of a hollow end plate or cover for the back of the radiator, a supplemental annular chamber for the same, and connecting passages therebetween, a fan, an annular chamber surrounding the fan, and connecting passages between the annular chamber surrounding the fan and the base for the circulation of water through the same, substantially as described and shown.

5. In radiators or coolers for motor road vehicles of the kind specified, provided with a back, the combination of a supplemental annular chamber formed on or fixed to the back of the radiator and provided with a series of short concave or tapered pipes or air ducts therethrough, a fan, an annular chamber surrounding the same, and a secondary cooling chamber for the passage of cool air to the motor, said air ducts communicating with the space between the said annular chamber surrounding the fan and the said secondary cooling chamber, substantially as and for the purpose described.

In witness whereof I have hereunto set my hand in the presence of two witnesses.

FRIEDRICH JOHANN DITRICH HÜLLINGHORST.
